UNITED STATES PATENT OFFICE.

RALEIGH J. HIMMELRIGHT, OF NEW YORK, N. Y., ASSIGNOR TO AMERICAN ARCH COMPANY, OF NEW YORK, N. Y., A CORPORATION OF DELAWARE.

LOCOMOTIVE FIRE BOX.

1,402,161.

Specification of Letters Patent. Patented Jan. 3, 1922.

Application filed May 4, 1917. Serial No. 166,305.

To all whom it may concern:

Be it known that I, RALEIGH J. HIMMELRIGHT, a citizen of the United States, residing at New York city, in the county of New York and State of New York, have invented certain new and useful Improvements in Locomotive Fire Boxes, of which the following is a specification.

This invention relates to improvements in locomotive fire boxes and has particular reference to fire boxes of the Gaines type, in which the fire box is divided into a fire chamber and a combustion chamber by means of a bridge wall extending across the fire box intermediate the flue sheet and the ends of the grates, means being provided in said bridge wall for introducing an additional supply of air.

One of the primary objects of my invention is the provision of a fire box of this general type in which better combustion and increase in general efficiency are obtained by introducing the additional air under automatic control.

One of the chief objects of the Gaines type of fire box is to obtain economy in the consumption of fuel and this has heretofore necessitated the provision of manually controlled mechanism for shutting off the additional air supply when the engine is not working. I propose to employ mechanism which automatically cuts off the additional air supply when the engine is not working, thus effecting a saving in fuel consumption, said means in addition regulating the volume of additional air supplied in proportion to the demands of the engine, as working conditions vary, as a result of which better combustion, economical operation and increase in general efficiency are obtained.

I accomplish the foregoing, together with such other objects as may hereinafter appear, by means of a construction illustrated in preferred form in the accompanying drawings, wherein:

Figure 1 is a longitudinal section through a Gaines fire box with my improvements applied thereto; Fig. 2 is a top plan of a detail of my invention; Fig. 3 is a section taken along the line III—III of Fig. 2; and Fig. 4 is a section taken on the line IV—IV of Fig. 3.

Referring now to Fig. 1, it will be seen that the fire box comprises the usual flue sheet 7, side sheets 8, back sheet 9, and

crown sheet 10. The bridge wall 11, which divides the fire box into the fire chamber A and combustion chamber B, is carried on the cross bearer 12 supported from the inside of the mud ring 13, such bridge wall 60 extending across the fire box, and being located in advance of the grates 14. The bridge wall is composed of fire brick or other suitable refractory material and is carried up to the circulation tubes 15 where 65 it cooperates with the rearwardly extending brick arch 16 carried on the tubes. In the bottom of the combustion chamber B is a discharge hopper 17 for the removal of deposit. Extending upwardly through the 70 bridge wall 11 and opening rearwardly therefrom beneath the arch 16 are one or more air supply passages or pipes 18. The air supply pipe is controlled by an automatic damper mechanism indicated as a 75 whole at C, such mechanism comprising a bellied or offset casing 19 having an opening 20 in the bottom thereof, such opening being controlled by a damper plate 21 pivotally mounted on the casing as indicated at 80 22. The plate 21 is pivoted at one side so that the area of the portion marked a is approximately three times the area of the portion marked b, as a result of which the plate 21 constitutes a differential damper 85 which normally is gravity held in closed position against the seats 23. The opening movement of the damper is limited by the stop 24.

The operation of the damper is as follows: 90 when the engine is not working, the normal draft through the grates supplies sufficient air for the economical maintenance of the fire and there is no draft or suction through the pipe 18, or at least the draft is not sufficient to cause the damper to open. When however the engine is working, owing to the partial vacuum created in the fire chamber, the suction through the upright supply pipe 18 will cause the damper to open because of 95 the unbalanced areas a and b, the degree to which the damper opens being dependent entirely upon the degree of suction which in turn is dependent upon the particular working conditions. If the engine is not working 100 hard, the damper will only open a slight distance or not at all, and if the engine is working hard, the damper may be widely opened. It will be apparent therefore that the volume of air supplied through the pipe 110

18 will be in direct proportion to the varying demands of the engine. Thus, whether the engine is idle or is working, air is supplied only in accordance with the demands, as a 5 direct result of which at all times better combustion and more economical consumption of fuel are obtained.

It will of course be understood that my 10 invention is applicable to other types of fire boxes than the specific one shown, my invention being directed to introduction of the additional air supply, regardless of the particular form of bridge wall or arch that is used, under automatic control, as demanded.

15 Another advantage incident to my improvement is that the damper is self-cleaning. This will be apparent from inspection of Fig. 3, from which it will be seen that any deposit will collect on the portion *b* of 20 the damper 21, which is directly under the pipe, and will be automatically discharged when the damper opens, the degree of inclination of the damper when fully opened being greater than the angle of rest.

25 I claim:—

1. A locomotive fire box construction operating under variable forced draft conditions comprising in combination, a supplemental air inlet and means for controlling 30 said inlet comprising a casing having a portion of its interior passage in line with said

inlet and an enlarged portion offset with respect to said inlet, a damper, and means for pivoting said damper at a point removed from an edge so as to provide unequal areas 35 at each side of the pivot line, the greater area being opposite the offset portion and the lesser area being opposite the inlet, said damper being adapted to increase the effective opening through the inlet as the locomotive is worked harder.

2. A locomotive fire box construction operating under variable forced draft conditions comprising in combination, a supplemental air inlet and means for controlling 40 said inlet comprising a casing having a portion of its interior passage in line with said inlet and an enlarged portion offset with respect to said inlet, a damper, and means for pivoting said damper at a point removed from an edge so as to provide unequal areas 45 at each side of the pivot line, the greater area being adapted to swing inwardly toward said inlet and the lesser area to swing outwardly away from the inlet 50 whereby accumulated deposit may be discharged and air may be admitted, said damper tending to increase the opening as the locomotive is worked harder.

In testimony whereof I have hereunto 55 signed my name.

RALEIGH J. HIMMELRIGHT.
